Gillmor, Mann & Cox
Atty's.

UNITED STATES PATENT OFFICE.

VIRGIL L. BEAUCHAMP, OF EVANSTON, ILLINOIS.

ATTACHMENT FOR HAIR CLIPPERS.

Application filed March 13, 1924. Serial No. 599,085.

To all whom it may concern:

Be it known that I, VIRGIL L. BEAUCHAMP, a citizen of the United States, and resident of Evanston, county of Cook, and 5 State of Illinois, have invented certain new and useful Improvements in Attachments for Hair Clippers, of which the following is a specification and which is illustrated in the accompanying drawings, forming a part 10 thereof.

This invention relates to hair clippers or clipping shears and more particularly to an attachment therefor.

One of the objects of the invention is the 15 provision of an attachment for hair clippers that constitutes a gage for clipping hair in various ways and to different lengths.

Other objects of the invention are the 20 provision of an attachment for hair clippers that is cheap to manufacture, efficient in operation, easy to manipulate, readily attached and one that is not likely to become broken or get out of order.

Other and further objects and advantages 25 of the invention will appear from the following description, taken in connection with the accompanying drawings, in which—

Fig. 1 is a perspective view of a pair of hair clippers showing the attachment in 30 position thereon;

Fig. 2 is a rear elevation thereof, with parts in section;

Fig. 3 is a plan view thereof, with parts in section;

Fig. 4 is a plan view of the attachment;

Fig. 5 is a side view thereof;

Fig. 6 is a rear elevation; and

Fig. 7 is a front elevation of said attachment.

On the drawings the reference character 40 10 designates a pair of hair clippers or clipping shears comprising the upper plate or jaw 11 to which the handle 12 is attached; the lower plate or jaw 13 provided with 45 the forwardly extending serrations or teeth 14; the movable or reciprocating knife or plate 15 having the forwardly extending serrations or teeth 16; and the handle 17 for reciprocating the plate 15;—all of which 50 are of the usual or any well known construction.

The teeth 14 and 16 are adapted to co-operate in the usual manner for cutting hair.

In cutting or trimming hair it is desir- 55 able that the hair on certain portions of the

head be cut or clipped shorter than it is at others. It is also desirable that the change from the shorter to the longer hair be not too abrupt but that the one gradually merge into the other.

A suitable attachment 20 for accomplishing these purposes has been provided and will now be described. The attachment comprises a plate 21 the upper face 22 of which is constructed to conform to the lower face 60 of the lower jaw or plate 13. The plate 21 is provided with guards or teeth 23 extending forwardly therefrom. The forward ends of the teeth or guards 23 are provided with upwardly extending projections 65 24 with which the ends of the teeth 14 engage when the attachment is in position thereon. In other words, the teeth or guards 23 are in alinement with the teeth 14 of the jaw 13 with which they are in contact. There 70 is a guard for each outside tooth of the lower jaw of the clipper and there may be a guard for every other tooth except in certain cases, as in the one shown, where the two middle teeth have no guards.

Suitable means are provided for detachably mounting the attachment on the plate or jaw 13. As shown, a clamping strip 25 is employed for this purpose. The strip 25 is secured in a groove in the upper face of 80 the plate 21 in such a manner that the upper face of said strip is flush with the upper surface of said plate. The ends of the strip are bent outward to form attaching clips 26 and 27. The clip 26 is curved inwardly 90 slightly more than the clip 27, whereby the plate 21 may be attached by placing the curved end 26 over the side edge of the plate or jaw 13 and pressing the plate into engagement with the lower face of said jaw. 95 A slight movement forwardly of the plate 21 suffices to position the same on the jaw 13.

The teeth or guards 23 decrease in thickness toward their forward ends. Preferably, though not necessarily, the plate 21 100 is curved upwardly at its forward end as shown at 28 in Fig. 5. The curve is a gradual one, thus enabling the operator to more easily rock the clippers on the curved engaging surface to graduate the length to 105 which the hair is cut than with the present type of clippers having a beveled instead of a curved lower surface. The teeth or guards 23 of the plate 21 are of gradually decreasing thickness from the center toward 110

each side. By this arrangement, the barber in operating the clippers around the sides and base of the head may by rocking the same laterally clip the hair exceedingly close adjacent to the ears and neck and of gradually increasing length toward the opposite end of the clippers.

For clipping the hair longer the clippers are held so that the lower surface of the middle guards or teeth only engages the head and by rocking the clippers longitudinally the hair may be clipped to the desired length. The curved surface enables the operator to more easily rock the clippers and hold the same in the proper position to cut hair to the desired length, than with clippers of the present construction wherein the lower surface of the teeth is beveled instead of curved.

20 The teeth or guards of the plate 21 are also of decreasing length from the middle toward each side. By this arrangement the longer guards enter the hair first and tend to feed the hair into the shorter guards. 25 This is especially advantageous when moving the clippers transversely to the direction in which the hair extends as when moving the clippers across the base of the head adjacent to the neck.

30 By making the outer teeth of the guard thin, a single pair of clippers may, in this manner, be manipulated to serve the purpose of a number of clippers that are at present necessary to clip hair short, medium and long.

When the attachment 21 is in position on the clippers the same may be considered as forming a part thereof, and when attached to the closest cutting type of clippers the latter may be employed to take the place of two or three extra clippers for cutting hair to different lengths, thereby eliminating the necessity of a barber possessing more than one pair of clippers.

45 It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:

1. In an attachment of the class described, a guard provided with teeth extending forwardly therefrom, means for detachably connecting said guard to a clipper head, said teeth being of progressively decreasing thickness and length from the center toward each side thereof. 55

2. An attachment for hair clippers, comprising a plate curved longitudinally at its forward end and teeth secured thereto and extending forwardly therefrom, said teeth being of increasing thickness from the longitudinal center to one side, and means for detachably connecting said attachment to a cutter head. 65

3. An attachment for hair clippers comprising a flat plate having its under surface curved upwardly at its forward end, teeth at the forward end of said plate, said teeth being of unequal length from the longitudinal center toward one side. 70

4. A guard for hair clippers provided with teeth extending forwardly therefrom, of decreasing thickness toward their forward ends, and of decreasing length from the longitudinal center to one side thereof, and means for detachably connecting said attachment to a cutter head. 75

5. An attachment for hair clippers, comprising a body portion provided with teeth extending forwardly therefrom and having their lower surfaces curved both longitudinally and transversely, and means for detachably connecting said attachment to a hair clipper. 85

6. An attachment for hair clippers comprising a plate provided with forwardly extending teeth, said teeth decreasing in thickness toward the front ends thereof, and decreasing in thickness from the middle toward each side of the plate, and a clip for holding said attachment onto the lower plate of the hair clippers. 90

7. An attachment for hair clippers comprising a plate having forwardly extending teeth or guards, the lower surface of said teeth being curved both longitudinally of and transversely to said plate, a retainer member secured to said plate and having its ends bent upward to form retaining clips. 100

VIRGIL L. BEAUCHAMP.
